FIG. 3.

UNITED STATES PATENT OFFICE.

WALTER S. BICKLEY, OF CHESTER, PENNSYLVANIA.

SAND-GRINDING APPARATUS.

1,147,362.

Specification of Letters Patent. Patented July 20, 1915.

Application filed February 17, 1914. Serial No. 819,139.

To all whom it may concern:

Be it known that I, WALTER S. BICKLEY, a citizen of the United States, residing in Chester, county of Delaware, State of Pennsylvania, have invented certain new and useful Improvements in Sand-Grinding Apparatus, of which the following is a specification.

My invention relates to sand grinding or sand crushing machines, or machines for operating upon earths or other materials.

My improved machine is particularly adapted to the grinding or preparation of molding sand, such as used in steel or other foundries.

It is the object of my invention to provide a machine, for operating upon sand or other material, which shall provide means for rolling sand or other material, mix it or turn it during treatment, and, at will, deliver the same out of the machine, it being particularly my object to provide such means which are simple in structure yet rugged, and efficient in operation.

My invention resides in a machine of the character hereinafter described.

For an illustration of one of the forms my invention may take reference may be had to the accompanying drawings, in which:

Figure 1 is a top plan view of the machine. Fig. 2 is a longitudinal sectional view, some parts in elevation, taken on the line A—A of Fig. 1. Fig. 2^a is a fragmentary sectional view, partly in elevation, showing a thrust bearing for a roller. Fig. 3 is a bottom plan view, some parts in section, taken on the line B—B of Fig. 2. Fig. 4 is a fragmentary side elevation of the shovel and neighboring parts. Fig. 5 is a vertical sectional view, some parts in elevation, taken on the line C—C of Fig. 1.

In the drawings, 1 is a base plate provided with pedestals 2 upon which is mounted an electric or other suitable motor M on whose rotatable shaft 3 is a pinion 4 which drives the sprocket chain or belt 5 which in turn drives the gear 6 secured upon the shaft 7 having bearings 8 carried by the base plate 1. On one end of the shaft 7 is a bevel pinion 9 which meshes with the bevel gear 10 which may be in sections, as shown in Fig. 3, and secured to the member 11 forming the bottom of a pan having the vertical rim 12, the rim 12 being secured by bolts 13 to the bottom 11, the bolts 13 extending through an outwardly turned flange on the

bottom of the rim 12. The bottom member 11 carries a central cylindrical bearing stud 14 which serves simply as a centering device for the member 11. The stud 14 has thereon a bearing sleeve 15 which rotates within the stationary bushing 16 carried in the boss 17 on the base plate 1. On the base plate 1 is a circular track 18, whose surface is preferably a portion of the surface of a cone, and on the track 18 bear the preferably conical rollers 19. These rollers 19 rotate upon and are carried upon the outer ends of the spokes or shafts 20 secured at their inner ends in the hub 21 having a central hole 65 embracing the boss 17, pins 22 serving to secure the shafts 20 in the hub 21. And near the rollers 19 the shafts 20 are spaced by the circular spacing member 23 secured to the shafts 20 by the straps 24. As shown 70 in Fig. 2^a, each roller is provided with a ball thrust bearing 19^a.

The bottom plate 11 of the pan rests upon the rollers 19 at the trackway 25, similar to the track 18. It will accordingly be understood that the pan rests upon and rotates upon the rollers 19 when the member 11 is driven by pinion 9 which in turn is driven by the motor M. At its center there is secured to the pan bottom 11 the member 26, 80 having cover 27, for confining the sand or material under treatment in an annular path between the outer walls of the member 26 and the rim 12 of the pan. Surrounding the member 26 is the ring shaped member 28 secured to the bottom plate 11. And between the ring 28 and the rim 12 of the pan are the wearing plate sections 29 secured to the bottom plate 11, these sections being here shown as four in number and constituting a false bottom. 90

Upon the base 1 are secured the yokes or pedestals 30 to which are secured the vertically slotted members 31, and in these vertical slots in members 31 engage the members secured by pins 33 to the shaft 34. Rotatable upon the shaft 34 are the hubs 35 having the flanges 36 each having a tapering or conical rim 37. And mounted upon each hub 35 is a member 38 having a tapering or conical ring 39. Bolts 40 pass through members 36 and 38 drawing them together thus securing the wearing shoe wheel members 41 of hard metal capable of better withstanding the wear incident to the 105 grinding and crushing of material. The inner sides of these rings 41 are preferably ta- 110

pered as indicated to correspond with the tapering ends 37 and 39. Between the hubs 35 is a sleeve 42, having oil hole 43, which holds the rollers or grinding wheels in the 5 positions indicated.

To the yokes or pedestals 30 are secured the arc shaped housing members 44 which closely embrace the rim 12 of the pan. These members 44 have horizontal inwardly 10 turned flanges 45 extending over the top edge of the pan rim 12. Secured to the members 44 and extending across the pan is the rod or bar 46. And supported at its one end upon the member 44 and at its other end 15 on the bar 46 is a bar 47. Secured to the bar 46 are the sand deflecting members 48. In Fig. 5 the member 49 is shown secured by set screws 50 to a vertically extending rod or bar 51 which is secured by member 52 to the 20 bar 47. The members 48 are supported on bar 46 by similar means.

Secured to one of the members 44 is the pivot pin 53 on which is pivoted the handle or arm 54, having counterweight 55. The 25 arm 55 carries the scoop or shovel 56, as seen in Figs. 1 and 4. The pivot pin 53 is placed in any suitable position, but preferably, as here shown, above and outside the pan. Near the scoop or shovel 56 is disposed the 30 preferably arc shaped plate 57 secured upon the member 44. To one side of the plate 57, in the direction of rotation of the pan, there may be placed a chute or spout 58 outside of the pan and carried by the member 44. In 35 front of this chute 58 may be placed a box 59 or other receptacle for the material delivered from the pan.

The operation is as follows: The motor M having been started, the pan is rotated by 40 pinion 9 driving the gear 10. The weight of the pan and the parts attached thereto and the sand or other contents insures the pinion 9 remaining in mesh with the gear 10. The pan revolves upon the rollers 19, the central 45 stud 14 serving as a centering device or guide. Sand or other material to be treated is put into the pan and as the pan rotates in the direction of the arrow, Fig. 1, the material is brought beneath the wheels 41 which, due to their frictional engagement 50 with the material, rotate in the direction of the arrows indicated in Fig. 1. These rollers are heavy and crush the sand or other material, or grind it, and as the thickness of 55 the sand in the bottom of the pan varies the rollers 41 rise and fall, the members 32 rising and falling in the slotted members 31. The members 48 and 49 keep deflecting the sand and turning it and mixing it so that all

of it sooner or later is operated upon by the 60 rollers 41. When the sand or other material has been sufficiently rolled or ground the attendant raises the handle 54, Fig. 4, from its normal dotted position, to the full line 65 position, whereupon sand or other material will move up along the shovel 56 and be discharged across the top flange 45 of the member 44 into the chute 58 from which it falls into the box or other receptacle 59, the pan continuing to rotate for this purpose. Then 70 other material or sand is put into the pan and so the operation is continued as long as desired, the contents being removed at will by operation of handle 54. The rims or 75 wheels 41 of the crushing or grinding rollers wear most rapidly on their outside edges. After they have become considerably so worn, they may be interchanged with each other in which case the part of each which had not previously worn so much will now 80 take the greater part of the wear. And the false bottom plates 29 are also preferably of material which will withstand wear, but when worn may be renewed.

The apparatus herein described is completely self contained, in that it may be removed from place to place, as in a foundry, by a crane, for grinding sand in any part of the foundry.

What I claim is:

In apparatus of the character described, the combination with a rotatable pan, of crushing rollers therein, a shovel, a pivotal shaft to which said shovel is secured at its one end, and a lever for rocking said shaft 95 secured to said shaft, the axis of said shaft being disposed above and outside of said pan, said shovel being of greatest width at its unsupported end adapted to lie near the bottom of said pan, one side of said shovel being curved to the shape of the inside of said pan, the opposite edge of said shovel having an upturned flange increasing in height from said unsupported edge toward the pivotal end of said shovel, whereby upon 100 operation of said handle said shovel is caused to engage in the pan contents and be deflected toward the bottom of said pan and to deliver said contents to the upper edge of 105 said pan.

In testimony whereof I have hereunto affixed my signature in the presence of the two subscribing witnesses.

WALTER S. BICKLEY.
